UNITED STATES PATENT OFFICE.

AXEL LEONARD ANDERSSON, OF LUND, SWEDEN.

COMBINED BOTTLING, CORKING, AND LABELING MACHINE.

Application filed November 4, 1925, Serial No. 66,877, and in Sweden December 27, 1924.

This invention relates to a combined bottling, corking and labeling machine, by means of which a great number of bottles may be treated simultaneously and successively. Hitherto the bottles have been transferred from one machine to another by means of known transport devices such as travelling conveyers or the like, and such devices require large space and complicated mechanisms to ensure the correct position of the bottles at their arrival at the various machines. The characteristic feature of the invention consists principally in arranging the various machines or apparatus in inter-spaced relation to each other around a circular table on which the bottles, guided in appropriate manner, are caused to intermittently move from one apparatus to the next, while at the same time special members, mounted on a continuously rotating disc, cause the various apparatus to operate during the time the bottles are stationary in position in register with said apparatus. The driving member for the rotating disc is connected with the member for effecting the intermittent movement of the bottles, so that a harmonious intercooperation of the said members is obtained. By this arrangement a very compact machine is produced in which the bottles are supplied in correct position to the various apparatus, and the usual transport devices employed between the apparatus become superfluous.

The invention is illustrated, by way of example, in the accompanying drawing, in which:—Fig. 1 shows the machine in a vertical section, and Fig. 2 shows the same in a top plan view; Fig. 3 is a detail view in side elevation of the intermittent feed device; Fig. 4 is a plan view of the continuously-rotating disc; and Figs. 5-7 are fragmental side views of the cams provided on said disc.

In the middle of the machine is vertically arranged a stationary column 1 provided with shoulders for receiving supporting members. In the example shown the parts of the machine are in addition supported by six brackets 2, 3, 4, 5, 6 and 7. The bracket 7 is provided with three bearings, the lowermost bearing 8 supporting the driving shaft 9 of the machine, while the intermediate bearing 10 supports an auxiliary shaft 11 and the uppermost bearing 12 supports another auxiliary shaft 13. The inner end of the driving shaft 9 has fixed thereto a bevel

gear wheel 14 which is in engagement with a toothed rim 15 on the disc 16, said disc being adapted to continuously rotate. On the outside of the bracket 7 the driving shaft 9 carries in addition a toothed wheel 17 which is in engagement with a toothed wheel 18 fixed to the projecting end of the auxiliary shaft 11, said toothed wheel 18 being provided with a feed member 19 which is adapted to periodically catch or pick up the successive studs 20 fixed to a disc 21 mounted on the end of the upper auxiliary shaft 13, thus imparting an intermittent rotary movement to said disc. The auxiliary shaft 11 also carries a disc-like member 211 provided at its circumference with recesses, which member serves to retain the disc 21 and thus also the auxiliary shaft 13 in definite positions in order to insure, as later on will be described more fully, the correct position of the bottles, during their stationary period, in register with the various apparatus. To the other end of the upper auxiliary shaft 13 is secured a bevel gear wheel 22 which is in engagement with a similar gear wheel 23 fixed to a sleeve 24 journaled by means of appropriate ball bearings on the column 1, said sleeve carrying radially extending pairs of plates 25 provided with apertures for the bottles. At a slight distance underneath the lower of these plates is arranged a stationary table 26, which is supported partly by the above named brackets 2 to 7 and partly by a bracket 27 mounted upon one of the shoulders on the column 1. This bracket 27 serves at the same time to support bearings for the ends of the auxiliary shafts 11 and 13 pointing towards the column 1. The disc 16 is supported at its center by ball bearings 28 and 29 mounted on the column 1 and at its circumference by a number of rollers 31 movably mounted on small brackets 30. The apparatus arranged for treating the bottles, such as bottling, corking and labeling apparatus are supported partly by the bracket 27, partly by the column 1 and partly by the brackets 4, 5 and 6 respectively. The members controlling the said various apparatus are at their lower portion provided with rollers which roll along cams or travelling paths arranged on the disc 16. These cams have profiles in vertical direction, so that the said controlling members are periodically raised and lowered respectively, whereby the various apparatus are thrown

into and out of operation respectively. In the example shown in Fig. 1, the cams 32, 33 for example are adapted to actuate the bottling apparatus, the cams 34, 35 to actuate the corking apparatus and the cam 36 to actuate the labeling apparatus. The cams 32, 33 and 36 are shown in section at the lowest portion of their profile and the cams 34, 35 at the highest portion of their profile. The disc 16 may in addition be provided with a cylindrical toothed rim 37 for obtaining movement for the mechanisms of the apparatus. It is to be observed that the apparatus may be of any known construction, wherefore it is not considered necessary to more fully specify the character of the profiles of the cams, which profiles obviously may have varying forms depending upon the type of apparatus which is to be used. By way of example a bottling apparatus of known type is shown in section in Fig. 1. The tank 38 containing the liquid to be filled into the bottles is mounted upon a platform 39 supported by the column 1 and the bracket 4, and at its underneath side is provided with discharge cocks 40. The plugs of the cocks are mounted on a common shaft 41, which is suitably connected with the rod 42 displaceable in its longitudinal direction, and by the movements of the rod the cocks may be opened and closed respectively. The other end of the rod is adjustably fitted by means of threads to the member 43, which may be moved up and down and which during its movements is guided by appropriate guides mounted on the brackets 27 and 4. This member is provided at its lower portion with a pair of rollers 44 rolling along the cams 32, 33 and at its upper portion provided with rods 45 slideable telescopically one into the other, each of said rods carrying a plate 46 which is let into the stationary table 26 in such a manner that its upper surface is level with the table. The bottles are placed in apertures in the radial plates 25 and adapted to slide at their bottoms upon the table.

When the plates 25 and thus also the bottles, succeeding their intermittent movement, are in position in register with the orifices 47 of the discharge cocks, the cams 32, 33 act on the rollers 44 of the member 43 so as to lift said member, whereby the plates 46 lift the bottles and press them against the orifices 47, and at the same time the cocks 40 are opened. As soon as the filling of the bottles is completed, the member 43 is lowered again, the cocks 40 are closed and when the bottoms of the bottles reach the table 26 the plates 25 together with the bottles are revolved one step further to the next apparatus, while a fresh supply of bottles will be fed to the bottling apparatus.

The machine is also provided with appropriate means for removing the finally

treated bottles and means for delivering new bottles into the machine, which means however do not pertain to this invention.

In Fig. 2, the numeral 48 designates the bottling apparatus, 49 the corking apparatus and 50 the labeling apparatus. According to the example shown in the drawing these three apparatus are arranged at angular distances of 60° in relation to each other, and therefore it is obvious that the gearing between the driving shaft, the disc 16 and the plates 25, must be such that the latter are revolved intermittently and comparatively quickly $\frac{1}{6}$ of a revolution at a time, while the disc 16 is revolved continuously and with uniform velocity, the cams thereon being provided with one or two elevations and depressions, depending upon whether the bottling, corking and labeling is desired, by correspondingly regulating the intermittent movement to take place once or twice for each revolution of the disc 16.

It is immaterial how many different apparatus are combined in the machine and at what distance in relation to each other they are arranged, or how the means for obtaining the intermittent movement of the plates carrying the bottles is constructed, because the characteristic feature of the invention principally consists in the combination of several apparatus in one machine and in obtaining the operations of the various apparatus by means of controlling members having profiles and fitted to a continuously rotating disc.

What I claim and desire to secure by Letters Patent is:—

1. A machine of the type set forth, comprising a plurality of bottle-treating mechanisms of different characters located at different definite stations of the machine; bottle-carrying means for moving bottles from one station to the next; a disc provided with cams for controlling the operation of the different bottle-treating mechanisms; a driving wheel; a wheel intermittently driven thereby; gearing between the driven wheel and the bottle-carrying means for intermittently rotating the latter; and separate gearing leading from the driving wheel to the cam disc for continuously rotating the same.

2. A machine of the type set forth, comprising in combination a stationary central column; a stationary circular table; a sleeve journaled on said column and provided with plates having apertures for the bottles, the plates being arranged above said table; a disc journaled on said column underneath said table; a number of bottle-treating mechanisms of different characters arranged around said table; cams on said disc in correspondence with such number of mechanisms; and acting to control the operation

of said mechanisms; a common driving means for the sleeve and the disc; gearing connecting said sleeve with said driving means to cause intermittent rotation of the sleeve; and gearing connecting said disc with said driving means to cause continuous rotation of the disc.

3. A machine of the type set forth, comprising a stationary central column; a stationary table; a carrier disposed above the table and having apertures for the bottles; a sleeve journaled on the column and to which the carrier is secured; a disc journaled on said column below said table; a

number of bottle-treating mechanisms of different characters arranged around said table; cams on said disc in correspondence with such number of mechanisms; and acting to control the operation of said mechanisms; a drive shaft; gearing between said shaft and said sleeve to intermittently rotate the sleeve; and gearing between the shaft and said disc for continuously rotating the disc.

In testimony whereof, I have signed my name to this specification.

AXEL ANDERSSON.
